UNITED STATES PATENT OFFICE.

RALPH K. THOMSON, OF SIOUX FALLS, SOUTH DAKOTA.

BROOM.

Application filed May 27, 1926. Serial No. 112,073.

This invention relates to improvements in brooms.

The primary object of this invention is the provision of an improved broom including a brush head or whisk portion formed of broom corn panicles held together in a novel fixed relation to most efficiently reinforce the same at the side edges of the broom.

A further object of this invention is the provision of an improved broom embodying a whisk of the conventional form having a novel type of stitching transversely across the handle connected end thereof, in which the spacing of the stitches is closer at the side margins of the broom than at the intermediate portion of broom whisk portion, to most efficiently reinforce and properly connect the broom with the stitching against liability of accidental and premature loosening.

Other objects and advantages of this invention will be apparent during the course of the following detailed description.

In the accompanying drawing, forming a part of this specification, and wherein similar reference characters designate corresponding parts throughout the several views,

Figure 1 is a side elevation of a broom of conventional shape, having the improved stitching formed as a part thereof.

Figure 2 is a side elevation of a broom in which the stitching is used as illustrated in Figure 1 of the drawings, although at both side marginal edges of the broom brush head.

Figure 3 is a somewhat diagrammatic representation of the form that the sewing thread takes when the same is stitched about the brush head of the broom.

In the drawing, wherein for the purpose of illustration are shown preferred and modified forms of this invention, the letters A and B may generally designate brooms of the corn whisk type including a brush head C having a handle D connected therewith, and respectively sewed by novel transverse rows of stitching E and F.

The brush head C of each of the forms of invention A and B consists of strands of any approved nature, preferably conventional broom corn, assembled in the flat manner as is quite ordinary, and connected to the handle D by wire clamping means 10. Adjacent the handle end of the brush head C the rows of stitching E and F are placed. This stitching E and F, as the case may be, is preferably placed by means of an improved broom sewing machine such as set forth in my co-pend-

ing application, Serial No. 58,153, filed Sept. 23, 1925, and the essential novelty of the invention consists in the placing of the transverse stitches in closer relation at the side 60 margins of the broom brush head than the spacing of the intermediate stitches. In the form of invention A illustrated in Figure 1, the spacing of the stitches in closest relation is effected only at the finishing side of the 65 brush head, that is, the side of the brush head which is stitched last, whereas the form of invention B has the stitchings at both side margins of the brush head spaced close together, with the intermediate stitches spaced 70 farther apart.

While the sewing of the stitches may be effected in any approved manner, and the thread may be handled in any relation desired, it is preferred to use the stitching illustrated in Figure 3 which consists in securing the thread at 15 adjacent one side margin of the brush head and then threading the same 80 at 16 transversely thru the thickness of the brush head C, and then wrapping the same at 17 and 18 twice peripherally about the brush head, to a location adjacent the transverse thread 16, and at which place the needle of the broom sewing machine starts the transverse loop stitching as at 20, which is extended back and forth in a zig-zag relation, first beneath the two rows of threads at one side of the brush head, and then transversely thru the brush head and beneath and over the two rows of threads at the opposite side of 85 the brush head C; the transverse stitching being somewhat diagonal as illustrated in Figure 3 of the drawings. The transverse lines of stitching are regulated as to their spaced relation by the novel step-by-step regulating means set forth in my application above referred to, so that the transverse stitches 25 at the side marginal portions of the brush head are spaced closer together than the intermediate transverse lines of 90 stitching 27 between the side marginal portions of the brush head C, as can readily be seen from Figures 1, 2 and 3 of the drawings.

Upon the finer grades of broom, such as the broom B, the side stitches 25 at each side 105 marginal portion of the brush head C are looped about the peripheral bands in a readily distinguishable closer spaced relation than the stitching 27. For other grades of brooms, however, such as the form of invention A, 110 the closer spaced stitches 25 are only provided at the finishing side of the broom, in

order to properly reinforce and hold the stitches in place to prevent the threads from working loose at the finishing end of the stitching.

5 From the foregoing description of this invention it is apparent that a novel stitching arrangement, and broom, as an article of manufacture have been provided, which provides a broom of extra reinforced quality 10 in so far as the securing of the whisks in the brush head are concerned, which will give durability and greater resiliency to the broom during use.

15 Various changes in the shape, size, and arrangement of parts may be made to the forms of invention herein shown and described, without departing from the spirit of the invention or the scope of the claims.

I claim:

20 1. As an article of manufacture a broom including a brush head secured together by means of transverse stitching, the stitches of said transverse stitching being disposed appreciably closer together at the side edges of the broom than at the intermediate portion thereof.

25 2. As an article of manufacture a floor broom including a conventionally shaped flat brush head formed of a plurality of pieces, 30 and stitches transversely disposed across the

thickness of the brush head comprising rows of stitching extending from side to side of the brush head, the stitches of said rows being disposed closer together adjacent the side edges or margins of the brush head than is 35 conventionally the practice and closer than the stitches at the intermediate portion of said brush head.

3. As an article of manufacture a broom including a brush head formed of a plurality 40 of pieces, a band substantially peripherally encompassing said brush head, and transverse stitching thru the brush head looped about said band, the stitching being formed to provide a plurality of closely spaced stitches at 45 the side marginal portions of the brush head and farther apart spaced stitches at the intermediate portion of the broom.

4. As an article of manufacture a broom including a brush formed of a plurality of 50 pieces, a band substantially peripherally encompassing said pieces to hold them in place, and transverse stitching thru the brush head looped about said encompassing band, the transverse stitching including a thread which 55 at the finishing edge of the brush head has the stitches thereof closer spaced together than elsewhere along the line of the encompassing band.

RALPH K. THOMSON.
